(57) **CLAIM**

The ornamental design for a coaster with bark-like side surface, as shown and described.

DESCRIPTION

FIG. 1 is a top, front perspective view of a coaster with bark-like side surface showing my new design.

FIG. 2 is a front view thereof.

FIG. 3 is a left side view thereof.

FIG. 4 is a rear view thereof.

FIG. 5 is a right side view thereof; and,

FIG. 6 is a top plan view thereof.

The broken line in the drawings is included to show a line that forms no part of the claimed design.
